UNITED STATES PATENT OFFICE.

FREDERICK C. NICKOL AND MILTON C. STERN, OF DAYTON, OHIO, ASSIGNEES TO THE
EGRY REGISTER COMPANY, OF DAYTON, OHIO, A CORPORATION OF OHIO.

AUTOGRAPHIC REGISTER.

1,104,127.

Specification of Letters Patent. Patented July 21, 1914.

Application filed July 12, 1911. Serial No. 638,068.

To all whom it may concern:

Be it known that we, FREDERICK C. NICKOL and MILTON C. STERN, citizens of the United States, residing at Dayton, in the county of 5 Montgomery and State of Ohio, have invented certain new and useful Improvements in Autographic Registers, of which the following is a specification, reference being had therein to the accompanying drawing.

10 This invention relates to autographic registers and more particularly to registers of that type in which a record is simultaneously made on a series of webs of paper, one of which is delivered as a check to the customer and another of which is retained in the machine as a record of the transaction.

The object of the invention is to provide 20 a register of this character with means for printing on one of the webs of paper a blank form or check to be filled in by the operator and to provide means for actuating this printing mechanism simultaneously with the operation of the feeding mechanism for the paper; and further, to provide an 25 inking device for the printing mechanism which, together with the printing mechanism and the feeding mechanism, will be operated from a single actuating member, thereby enabling the complete operation of 30 the machine to be accomplished with a minimum amount of movement on the part of the operator.

It is also an object of the invention to 35 provide means for inking each part of the type before it comes in contact with the paper; to provide means to maintain the printing roller normally out of engagement with the platen; and to positively move the same into engagement therewith at the beginning of the printing operation.

It is a further object of the invention to so construct and support the printing mechanism and inking device therefor that a part 45 of these devices can be moved relatively to the other part thereof to permit of ready access to any part or parts thereof; to provide means to prevent the movement of the printing roller relatively to the platen when it has been moved into position to permit access to the printing devices; and to provide 50 means for adjusting the inking device to regulate the amount of ink transferred to the printing roller.

In the accompanying drawings, Figure 1 55 is a top, plan view of a register embodying

our invention, with the casing removed and showing the handle in section; Fig. 2 is a longitudinal sectional view of the same; Fig. 3 is a side elevation of a portion of the mechanism showing the operating handle; Fig. 4 is a sectional, detail view, taken on the line $\alpha\alpha$ of Fig. 1 and looking in the direction of the arrows; and Fig. 5 is an end elevation of the supplemental frame supporting the printing and inking rollers.

In these drawings we have illustrated one embodiment of our invention and have shown the same as comprising a main frame consisting of side members 1 and 2 connected one to the other by suitable tie rods 3. 70 This frame is provided with means for supporting one or more webs of paper between the side members thereof, and, in the present instance, we have shown the webs of paper as put up in rolls and have shown supports for three such webs, each support comprising a shaft 4 mounted in the side members of the frame and having its roll of paper 5 rotatably mounted thereon in a well known manner. The webs of paper are drawn from the several rolls toward the forward end of the machine, about suitable guides, and are carried in superimposed relation over a writing table 6 supported upon the side members of the main frame. The 75 guides about which the paper passes may be of any suitable character. In the present instance two of these guides are shown as rods 7 supported in the side members of the frame and the third guide comprises a platen 8 of a printing mechanism to be hereinafter described. Suitable feeding mechanism is provided for drawing the paper from the rolls and feeding the same across the writing table. This mechanism is preferably arranged beyond the writing table and is here 80 shown as comprising a pair of feeding rollers. The larger and lowermost of these rollers, which is indicated at 10, is journaled in the side members of the main frame immediately in the rear of the writing table, and has one end of its shaft 11 projecting beyond one of said side members and provided with means for rotating the feed roller. The second and smaller roller 12 is arranged immediately above the roller 10 and is preferably movable into and out of operative relation thereto. To this end the end portions 85 or trunnions 13 of the roller 12 are mounted in slots 14 formed in brackets 15 extending

95

90

95

100

105

111

upwardly from the respective side members of the frame.

The brackets 15 are provided with vertical recesses in which are mounted springs 16 which bear upon the trunnions of the upper feed roller and tend to move the same toward the lower roller and into operative relation therewith. Means are provided for moving the upper roller away from the lower roller to permit the webs of paper to be passed between the same or adjusted relatively thereto and for this purpose we have, in the present machine, provided two plates 17 arranged near the opposite sides 15 of the machine and having their forward ends slightly tapered and extending between the shaft of the lower roller and the trunnions of the upper roller. The rear ends of these plates are pivotally connected to crank arms 18 which are mounted on a shaft 19 journaled in the side members of the frame and having one end projecting beyond one of said side members and provided with a handle or thumb piece 20 by 25 means of which the shaft 19 may be rocked. It will be apparent that when the shaft 19 is rocked in a direction to move the crank arms 18 and the plates 17 forward the inclined edges of the plates will force the rollers 30 apart and that when these plates are moved rearward the springs 16 will move the upper roller toward the lower roller. It will further be noted that the frictional contact between the plates and the shaft of the lower 35 roller and the trunnions of the upper roller is such that the movement of these rollers about their axes will move the plates rearwardly and permit the upper roller to assume its operative position relatively to the lower roller, this action taking place on the 40 first movement of the feeding device.

Suitable mechanism is provided for printing upon one or more of the webs of paper before the part or parts printed upon reach 45 the writing table. In the present instance we have arranged this mechanism to print upon the web of paper passing from the foremost roller, this web being the uppermost of the webs, as they lie upon the writing table, but it will be obvious that any 50 other of the webs could be printed upon by merely shifting the position of the printing mechanism or duplicating the same. The printing mechanism preferably comprises 55 a printing roller and rotary platen co-operating therewith and in order that we may print upon the uppermost web of paper we have arranged the printing mechanism near the forward end of the frame and have 60 mounted the platen 8 upon a shaft 21 journaled in fixed bearings in the side members of the main frame. The printing roller may be of any suitable character and may be supported in any suitable manner. As here 65 shown it comprises a roller of metal, as indi-

cated at 23, mounted on a shaft 24 and provided on its outer surface with suitable type which may be in the form of a type sheet 25 of rubber or other suitable material having the type and lines to be printed molded in the same. The platen 8 and the printing roller 23 are provided with and connected one to the other by intermeshing gears 26 and 27, respectively, to cause the same to rotate in unison. Movement may be imparted to these rollers in any suitable manner, but they are preferably operated in unison with the feeding mechanism, and, to this end, the shaft of the platen 8 is shown as projecting beyond the side walls 2 of the main frame and provided with a miter gear 28 which meshes with a corresponding gear 29 on a shaft 30 journaled in bearing brackets 31 secured to the side members of the frame. This shaft has at its rear end a second miter gear 32 meshing with a miter gear 33 loosely mounted on the shaft 11 of the feeding roller 10 and provided with a handle 34 for actuating the same.

An inking device comprising a roller 35 is supported in a position to engage the printing roller 23 and ink the type thereon. This inking roller has a gear 22 meshing with the gear 27 of the printing roller to cause the inking roller to rotate in unison with the printing roller. There is necessarily a portion of the surface of the printing roller lying between the point of contact of the printing roller with the platen and the point of contact of the printing 95 roller with the inking roller, which, upon the normal operation of the device, would not come in contact with the inking roller and if the machine had been standing idle for a length of time sufficient to permit the ink to dry on the type an imperfect impression would be secured upon the first rotation of the printing roller. To avoid this and secure a perfect impression upon the first operation of the device we have provided means whereby this portion of the printing roller may be inked before the feeding devices are actuated. This is accomplished by rotating the printing roller and inking roller in a rearward direction a 100 distance sufficient to bring the type lying between the inking roller and the platen into engagement with the former. It is desirable, however, that the paper should not be actuated during this preliminary inking 105 operation and we have, therefore, so constructed the operating mechanism that when the printing roller is rotated in a rearward direction a distance sufficient to accomplish this preliminary inking the feeding mechanism will remain idle, and further we have so constructed the mechanism that the printing roller will be moved out of operative engagement with the paper and the rotation 110 thereof will not blur the ink on the paper. 115

The first of these results is secured by so connecting the operating handle 34 with the shaft 11 of the feed roller 10 that the handle is capable of a certain amount of movement independently of the roller. As above stated, the handle is loosely mounted on the shaft 11, and, in order that the shaft may be caused to rotate with the handle in the normal operation of the device, a cross bar 36 is rigidly secured to the end of the shaft and provided with inwardly extending lugs 37 arranged to be engaged by the handle 34 and limit the movement of the latter relatively to the shaft 11. The feeding roller 10 is held against rearward movement by a spring-pressed pawl 38, and, consequently, the forward lug 37 serves merely as a stop to limit the motion of the handle 34 in a reverse direction. When the handle is rotated in a forward direction it will engage the rear lug 37 and cause the shaft 11 and feeding mechanism to rotate with the handle. In this connection it will be noted that a single rotation is imparted to the large feed roller 10 upon each operation of the mechanism, and, in this manner, a measured check is delivered, that is, each and every check delivered by the machine is of exactly the same length. To this end a stop is provided to check the movement of the feed mechanism when the roller 10 has completed a single revolution. As here shown the handle 34 is provided with a spring-pressed pin 39 which normally projects beyond the inner side of the handle and in a position to engage a lug 40 projecting from the side member 2 of the main frame. The hand piece 41 of the handle 34 is connected with the spring-pressed pin 39 and an outward movement of the hand piece will withdraw the pin 39 and permit the handle to be moved in a direction to actuate the feeding mechanism. The projection 40 is preferably provided in its outer end with a recess 42 to receive the end of the pin, thereby enabling the feeding mechanism to be positively locked against accidental movement in either direction, this being desirable when the printing mechanism shall have been rendered inoperative for any reason.

As stated, the printing roller is moved out of engagement with the platen or the paper thereon during the preliminary inking of that portion of the printing roller between the platen and the inking roller. This movement of the printing roller is preferably controlled by the movement of the feeding mechanism, and, in the form of the device here shown, we have provided means for retaining the printing roller normally out of engagement with the platen, that is, when the machine is idle these two rollers will be out of engagement one with the other. This not only prevents the smearing of the ink on the paper should any movement be imparted

to the inking roller, but also prevents the type on the printing roller from making indentations in the platen due to a long standing contact between the rollers. To permit of this movement of the inking roller it is mounted in a supplemental frame 43 comprising side members connected together by a tie bar 44 and rigidly secured at its lower end to a shaft 45 journaled in the side members 1 and 2 of the main frame. This particular form of support for the printing roller is chosen for a purpose which will hereinafter appear and it will be obvious that the printing roller may be movably supported in any suitable manner. Movement toward and away from the platen is preferably imparted to the printing roller by the operation of the feeding mechanism and the connection between the feeding roller and the printing roller is such that the printing roller is moved positively into its operative position or into contact with the platen. In this manner the degree of pressure exerted by the one roller on the other may be positively regulated and a uniform impression secured. The particular mechanism here illustrated comprises a disk 46 rigidly secured to the shaft 11 of the feeding roller 10 and having in one side thereof a notch 47. A lever 48 is pivotally mounted on the main frame and provided with a lateral projection, such as a roller 49, adapted to enter the recess 47 when the latter is brought into alignment therewith and to be forced out of the recess when the disk is rotated with the feeding roller. The arm 48 is connected to the printing roller in such a manner that the rocking movement imparted to the arm 48 by the movement of the roller 49 into and out of the recess 47 will impart the desired movement to the printing roller. As here shown a second lever 50 is pivotally mounted on the main frame between the lever 48 and the printing roller. Both the levers 48 and 50 are pivotally supported between their ends and the lower ends of the levers are connected one to the other by a link 51 and the upper end of the lever 50 is connected by a link 52 with the supplemental frame 43 in which the printing roller is mounted. The projection or roller 49 of the lever 48 is located in the rear of the disk 46, and, consequently, it will move rearwardly when forced out of the notch in the disk, and, through the connecting devices, will impart a rearward movement to the printing roller. The link 52 is preferably formed in two parts which are connected one to the other by bolt and slot connections, as indicated at 53, thus enabling the length of the link to be adjusted to regulate the position of the printing roller relatively to the platen. The roller 49 is caused to enter the recess in the disk 46 and the printing roller 23 is moved away from the 130

1 platen by the action of a spring 71 which is connected at one end to the link 51 and at the other end to the main frame. It will be noted that the printing roller is positively moved into its operative position, thus causing the same to be moved into and maintained in an exactly correct position and enabling uniform records to be secured. It will also be noted that the type sheet carried by the printing roller is of a length slightly greater than the length of the form which is to be printed. As a result at the abutting ends of this sheet there is a space between the top and bottom of the form which contains no type. Preferably, the printing roller is so arranged with relation to the inking roller that when the parts are in their idle positions this space between the top and bottom of the type of the form will lie adjacent to the inking roller. Consequently, the type of the form will not be in engagement with the inking roller when the machine is idle and there will be no distortion of the type or indentation of the inking roller due to a long continued contact between these parts.

2 The connection between the link 52 and the supplemental frame is shown as comprising a recess 54 formed in the lower side 30 of the forward end of the link and adapted to receive the tie bar 44 at the upper part of the supplemental frame. The link thus forms a latch which serves to normally support the supplemental frame and the parts carried thereby in their upright or normal positions but which may be released therefrom to permit the supplemental frame to move about the axis of the shaft 45. The movement of the supplemental frame about 35 the axis of the shaft 45 carries the printing roller 22 and the inking roller 35, which is also mounted on this frame, away from the platen and into positions which will permit of ready access to all parts of the printing mechanism. To prevent the printing roller from rotating and thus altering its position relatively to the platen 8 when the supplemental frame has been moved into its lowermost or inoperative position a suitable retaining device is provided which is here 40 shown as a pawl 55 loosely mounted on the tie bar 44 and connected thereto by a spring 56 which tends to move the pawl toward the gear 27 of the printing roller. A stop, such as a pin 57, is secured to the adjacent side member of the main frame in a position to engage the pawl and hold the same out of engagement with the gear when the supplemental frame and the printing roller are in 45 their uppermost or normal positions. When the supplemental frame is moved downward the pawl will be carried out of engagement with the pin and the spring will move it into engagement with the gear, thus locking the 50 gear against movement.

5 The inking roller is mounted in the supplemental frame 43 in such a manner as to permit of its ready removal should it be desired to clean the same or renew the ink supply and also to permit of its adjustment 55 relatively to the printing roller so that the amount of ink delivered to the printing roller can be regulated. The inking roller is carried by a shaft 58, the ends of which project beyond the corresponding ends of the roller and are mounted in slots 59 formed in the respective side members of the supplemental frame 43. The slots 59 are provided with rearwardly extending openings 60 through which the shaft of the roller may 60 be inserted in the slots 59. These openings are normally closed by arms 61 supported on a shaft 62 journaled in the side members of the supplemental frame. A lever 63 is rigidly secured to the shaft 62 on the outer side of the main frame, and, by manipulating this lever, the arms 61 can be moved toward or away from the openings 60 leading to the slots 59. The lever is normally locked in a position to retain the arms 61 across the 65 openings 60 and prevent the removal of the inking roller. This locking device is here shown as comprising a pawl 64 pivotally mounted on the lever and adapted to engage a notch 65 in the adjacent side member of the supplemental frame when the arms are in their normal positions, that is, in their positions closing the openings to the slots. The slots 59 are preferably inclined toward the printing roller and the tendency of the 70 inking roller is to move away from the printing roller. To hold the inking roller in engagement with the printing roller we have provided arms 66 at the ends of the inking roller which extend beneath the shaft 58 and, 75 support the roller in the desired position. These arms are mounted upon a shaft 67 journaled in the side members of the supplemental frame and this shaft is provided with a slotted crank arm 68. The shaft 45, to 80 which the supplemental frame is rigidly secured, is provided with an arm or bracket 69 having a screw-threaded aperture in which is mounted a screw 70 having its inner end provided with an annular groove to enable it to enter the slot in the crank arm 67. The width of the groove in the end of the screw is substantially equal to the thickness of the crank arm and the screw has little or no longitudinal movement relatively to the 85 crank arm and, therefore, any longitudinal movement of the screw will impart a corresponding rocking movement to the shaft 67 and will cause the supporting arms 66 to change their positions relatively to the 90 slots 59.

95 After the several webs of paper have passed beyond the writing table and the feeding mechanism the two uppermost sheets are removed and the remaining or lower- 100

most web is rewound upon a rewinding roller 72 supported within the main frame and actuated by suitable gearing 73 from the feeding mechanism, thus retaining this web 5 and the records made thereon as a permanent record.

The operation of the machine will be readily understood from the foregoing description and it will be apparent that we 10 have provided a mechanism whereby the desired printed matter can be impressed upon a portion of a web of paper before the said portion arrives in position above the writing table where the record is made; that the 15 mechanism is of such a character that a uniform impression can be secured, that the parts can be held in such relation one to the other as to prevent injurious contact between them, that the several parts are positively actuated; and that the feeding mechanism, printing mechanism and inking device can all be actuated by means of a single actuating member or handle.

While we have shown and described one 25 form of our invention it will be understood that we have chosen the same for the purpose of illustration only and we do not desire to be limited to the details of construction shown and described, for obvious modifications will occur to a person skilled in the art.

Having thus fully described our invention, what we claim as new and desire to secure by Letters Patent, is:—

35 1. In an autographic register, the combination, with a support for a web of paper, a writing table, printing mechanism arranged to act on said web of paper between the support therefor and said writing table, an inking device for said printing mechanism, and feeding mechanism to move said paper over said writing table, of operating mechanism comprising a single actuating member, to impart movement to said inking 40 mechanism, said feeding device and said printing mechanism.

2. In an autographic register, the combination, with a frame having means to support a web of paper, a writing table carried 50 by said frame, feeding rollers mounted on said frame to move said paper over said writing table, a printing roller arranged to act upon said paper between said supporting means and said feeding rollers, and an inking device for said printing roller, of a single operating handle to actuate said feeding rollers, said printing roller and said inking device.

3. An autographic register comprising a 60 frame, means to support a web of paper on said frame, a writing table carried by said frame, feeding mechanism to move the paper from said web over said writing table, printing mechanism mounted on said frame 65 to print on said paper before the latter

reaches said writing table, an inking device for said printing mechanism, and an actuating member operatively connected to said feeding mechanism, said printing mechanism and said inking device.

4. In an autographic register, the combination, with a frame, means for supporting a web of paper on said frame, a writing table carried by said frame, and feeding mechanism arranged beyond said writing 75 table, of a printing roller carried by said frame and arranged to act on said web of paper between the support therefor and said writing table, a platen mounted in said frame, and means for simultaneously actuating said feeding mechanism and said printing roller.

5. In an autographic register, the combination, with a frame, means for supporting a web of paper on said frame, a writing table carried by said frame, and feeding mechanism arranged beyond said writing table, of a printing roller carried by said frame and arranged to act on said web of paper between the support therefor and said writing table, a platen mounted in said frame, means for simultaneously actuating said feeding mechanism and said printing roller, and means for imparting movement to said printing roller independently of said feeding mechanism.

6. In an autographic register, the combination, with a frame, means for supporting a web of paper on said frame, a writing table carried by said frame, and feeding mechanism arranged beyond said writing table, of a printing roller carried by said frame and arranged to act on said web of paper between the support therefor and said writing table, a platen mounted in said frame, means for simultaneously actuating said feeding mechanism and said printing roller, means for imparting movement to said printing roller independently of said feeding mechanism, and means for maintaining said printing roller in an inoperative position during said independent movement thereof.

7. In an autographic register, the combination, with a frame, means for supporting a web of paper on said frame, a writing table carried by said frame, and feeding mechanism arranged beyond said writing table, of printing mechanism arranged to act on said web of paper between the support therefor and said writing table and comprising a platen and a printing roller movable toward and away from said platen, an inking device for said printing roller, means for imparting movement to said printing roller in one direction simultaneously with the movement of said feeding mechanism and for imparting movement to said printing roller in another direction independently of said feeding mechanism to cause that por- 125

tion of said printing roller lying between said platen and said inking device to come in contact with the latter.

8. In an autographic register, the combination, with a frame, means for supporting a web of paper on said frame, a writing table carried by said frame, and feeding mechanism arranged beyond said writing table, of printing mechanism arranged to act on said web of paper between the support therefor and said writing table and comprising a platen and a printing roller movable toward and away from said platen, an inking device for said printing roller, means for imparting movement to said printing roller in one direction simultaneously with the movement of said feeding mechanism and for imparting movement to said printing roller in another direction independently of said feeding mechanism to cause that portion of said printing roller lying between said platen and said inking device to come in contact with the latter, means for maintaining said printing roller in an inoperative position during the second of said movements, and other means for positively moving said printing roller into its operative position during the first of said movements.

9. In an autographic register, the combination, with a frame, means for supporting a web of paper on said frame, a writing table carried by said frame, and feeding mechanism arranged beyond said writing table, of printing mechanism arranged to act on said web of paper between the support therefor and said writing table and comprising a platen and a printing roller movable toward and away from said platen, an inking device for said printing roller, means for imparting movement to said printing roller in one direction simultaneously with the movement of said feeding mechanism and for imparting movement to said printing roller in another direction independently of said feeding mechanism to cause that portion of said printing roller lying between said platen and said inking device to come in contact with the latter, means for maintaining said printing roller normally in an inoperative position, and means controlled by the movement of said feeding mechanism for moving said printing roller into an operative position.

10. In an autographic register, the combination, with a frame, a support for a web of paper on said frame, a writing table, printing mechanism arranged to act on said web of paper between the support therefor and said writing table and comprising a platen and a printing roller movable toward and away from said platen, an inking device for said printing roller, and feeding mechanism comprising a rotatable shaft, of an operating handle, a connection between said oper-

ating handle and said printing mechanism to cause the latter to be actuated upon the movement of said handle in either direction, and means for connecting said handle with said rotatable shaft to cause said feeding mechanism to be actuated when the handle is moved in one direction only.

11. In an autographic register, the combination, with a frame, a support for a web of paper on said frame, a writing table, printing mechanism arranged to act on said web of paper between the support therefor and said writing table and comprising a platen and a printing roller movable toward and away from said platen, an inking device for said printing roller, and feeding mechanism comprising a rotatable shaft, of a handle loosely mounted on said shaft, a positive connection between said shaft and said printing mechanism to cause the latter to be actuated when said handle is moved in either direction, and means for connecting said handle to said rotatable shaft when the handle is moved in one direction to cause said feeding mechanism to be actuated.

12. In an autographic register, the combination, with a frame, a support for a web of paper on said frame, a writing table, printing mechanism arranged to act on said web of paper between the support therefor and said writing table and comprising a platen and a printing roller movable toward and away from said platen, an inking device for said printing roller, and feeding mechanism comprising a rotatable shaft, of a handle loosely mounted on said shaft, a positive connection between said shaft and said printing mechanism to cause the latter to be actuated when said handle is moved in either direction, means for connecting said handle to said rotatable shaft when the handle is moved in one direction to cause said feeding mechanism to be actuated, a part carried by said rotatable shaft and operatively connected with said printing roller to move the same toward said platen when said feeding mechanism is actuated, and means to move said printing roller away from said platen when said feeding mechanism is in its normal or idle position.

13. In an autographic register, the combination, with a frame, a support for a web of paper on said frame, a writing table, printing mechanism arranged to act on said web of paper between the support therefor and said writing table and comprising a platen and a printing roller movable toward and away from said platen, an inking device for said printing roller, and feeding mechanism comprising a rotatable shaft, of a handle loosely mounted on said shaft, a positive connection between said shaft and said printing mechanism to cause the latter to be actuated when said handle is moved in either direction, means for connecting

5 said handle to said rotatable shaft when the handle is moved in one direction to cause said feeding mechanism to be actuated, a disk rigidly secured to said shaft and having a recess in the edge thereof, a lever pivotally mounted on said frame and having a part adapted to enter the recess in said disk, and a connection between said lever and said printing roller.

10 14. In an autographic register, the combination, with a frame, a support for a web of paper on said frame, a writing table, printing mechanism arranged to act on said web of paper between the support therefor and said writing table and comprising a platen, and a printing roller, an inking device for said printing roller, and feeding mechanism comprising a rotatable shaft, of a handle loosely mounted on said shaft, a positive connection between said shaft and said printing mechanism to cause the latter to be actuated when said handle is moved in either direction, means for connecting said handle to said rotatable shaft when the handle is moved in one direction to cause said feeding mechanism to be actuated, a disk rigidly secured to said shaft and having a recess in the edge thereof, a lever pivotally mounted on said frame and having a part adapted to enter the recess in said disk, and an adjustable connection between said lever and said printing roller.

15 15. In an autographic register, the combination, with a frame, a support for a web of paper on said frame, a writing table, printing mechanism arranged to act on said web of paper between the support therefor and said writing table and comprising a platen and a printing roller movable toward and away from said platen, an inking device for said printing roller, and feeding mechanism comprising a rotatable shaft, of a handle loosely mounted on said shaft, a positive connection between said shaft and said printing mechanism to cause the latter to be actuated when said handle is moved in either direction, means for connecting said handle to said rotatable shaft when the handle is moved in one direction to cause said feeding mechanism to be actuated, a disk rigidly secured to said shaft and having a recess in the edge thereof, a lever pivotally mounted on said frame and having a part adapted to enter the recess in said disk, a link connection between said lever and said printing roller, whereby the rotation of said disk will move said printing roller into an operative position, and a spring to move said printing roller into an inoperative position.

20 16. In an autographic register, a frame, a support for a web of paper on said frame, a writing table, a feeding mechanism for said paper comprising a rotatable shaft, of a printing mechanism arranged to act on said

25 web of paper between the support therefor and said writing table, a handle loosely mounted on said shaft, and a cross bar rigidly secured to said shaft and having projections arranged on the opposite sides of said handle.

30 17. In an autographic register, the combination, with a frame, a writing table therefor, a support for a web of paper, means for feeding said paper over said writing table, and a platen mounted on said frame, of a printing roller mounted for bodily movement on said frame, and means actuated in unison with said feeding means to move said roller bodily toward said platen.

35 18. In an autographic register, the combination, with a main frame, a writing table therefor, a support for a web of paper, and means for feeding said paper over said writing table, of a supplemental frame movably mounted on said main frame, a printing roller carried by said supplemental frame, and means for actuating said supplemental frame in unison with said feeding means to move said printing roller into and out of operative relation with said web of paper.

40 19. In an autographic register, the combination, with a main frame, a writing table therefor, a support for a web of paper, means for feeding said paper over said writing table, and a platen mounted on said main frame, of a supplemental frame movably mounted on said main frame, a printing roller carried by said supplemental frame, means to actuate said supplemental frame to move said printing roller toward and away from said platen, and means for locking said printing roller against rotation when said frame has been actuated to move said printing roller away from said platen.

45 20. In an autographic register, the combination, with a main frame, a writing table therefor, a support for a web of paper, means for feeding said paper over said writing table, and a platen mounted on said main frame, of a supplemental frame movably mounted on said main frame, means to actuate said supplemental frame to move said printing roller toward and away from said platen, a pawl to hold said printing roller against rotation, and means controlled by the movement of said supplemental frame to actuate said locking device.

50 21. In an autographic register, the combination, with a main frame, a writing table therefor, a support for a web of paper, and means for feeding said paper over said writing table, of a supplemental frame movably mounted on said main frame, a printing roller carried by said supplemental frame, and actuating mechanism operatively connected with said feeding mechanism and with said supplemental frame to cause said supplemental frame to be actuated to move said printing roller into engagement with

said web of paper and to then cause the web of paper to be fed forward relatively to said printing roller and said writing table.

22. In an autographic register, the combination, with a main frame, a support for a web of paper, a writing table mounted on said frame, a platen, and feeding mechanism to move said paper over said platen and said writing table, of a supplemental frame 5 movably mounted on said main frame, a printing roller carried by said supplemental frame and adapted to be moved toward and away from said platen, and an operative connection between said feeding mechanism 10 and said supplemental frame, whereby the operation of said feeding mechanism will cause said roller to be moved into printing engagement with the paper.

23. In an autographic register, the com-

bination, with a main frame, a support for 20 a web of paper, a writing table mounted on said frame, a platen, and feeding mechanism to move said paper over said platen and said writing table, of a supplemental frame 25 movably mounted on said main frame, a printing roller carried by said supplemental frame and adapted to be moved toward and away from said platen, and a single actuating member operatively connected with said feeding mechanism, said supplemental frame 30 and said printing roller.

In testimony whereof, we affix our signatures in presence of two witnesses.

FREDERICK C. NICKOL
MILTON C. STERN.
